UNITED STATES PATENT OFFICE

WILLIAM H. MUSSEY, OF CHICAGO, AND JULIAN R. RUDULPH, OF HOMEWOOD, ILLINOIS,
ASSIGNORS, BY MESNE ASSIGNMENTS, TO PULLMAN CAR & MANUFACTURING
CORPORATION, A CORPORATION OF DELAWARE

DUMP CAR DOOR

Original application filed May 15, 1931, Serial No. 537,636, Patent No. 1,859,261, May 17, 1932. Divided
and this application filed October 12, 1931. Serial No. 568,338.

The invention relates generally to discharge doors for dump cars and particularly adapted to hopper cars of the type indicated in co-pending application filed May 15, 1931, Serial No. 537,636, now Patent 1,859,261, granted May 17, 1932, of which this application is a division.

One object of the invention is to provide a door construction having a plane face panel portion presented to the lading and fashioned at its upper edge to provide a combined hinge section and stiffening element for that portion of the door.

Another object is to provide a door fabricated of pressed metal parts welded together and disposed and proportioned to form a unitary structure especially adapted to sustain a load imposed between its ends and designed to engage locking devices at opposite sides of the car.

The foregoing and other objects are attained by the structure illustrated in the accompanying drawing, in which

Figures 1, 2, and 3, show respectively an outside elevational view of the door, an end view, and a vertical sectional view taken on line 3—3, of Figure 1, showing the contour of the door hinge portion and door plate stiffeners; and

Figures 4 to 6 inclusive, show respectively and on a larger scale, and door mounted on the car, in full open, normally hung, and closed positions, respectively.

In the drawing, the door 138 for closing discharge openings upon opposite sides of the center sill 10 is preferably in one piece with a central opening 140 to clear the center sill and brake rod 127 during opening movements, as best shown in Figure 1, and made up of a continuous body plate portion 141 having its upper margin fashioned to provide a hinge section 142 and reinforced by relatively vertical intermediate channel stiffening members 143 and 144 spaced apart and traversing the door from top to bottom thereof,

and relatively inclined end stiffeners 145, severally united to the door panel 141 by welding, preferably along the edges of the flanges 146 of the stiffeners, as best shown in Figures 1, 2, and 3.

The hinge section 142 is shaped to lend rigidity to that part of the door and formed with an outwardly bulged portion 147 having an inwardly and downwardly extending flange 148 terminating in a curved rebent edge 149, adapted to engage an associated retaining connection 150 designed to interlock with a hinge section 109 welded to the underside of the intermediate sloping floor plates 101 at the respective door openings, and co-operating therewith to pivotally support the doors. To preserve the contour of the door hinge portion 142, the flanges 146 of respective stiffeners 143, 144 and 145 are cut out to conform to the bulged portion 147 of the hinge and fillet welded as shown.

The door is further strengthened by the addition of rigidifying longitudinal edge members 151 disposed upon opposite sides of central opening 140 and extending therefrom across the upper ends of respective stiffeners 143, 144 and 145 to which they are welded, to points adjacent the door ends. As shown in Figures 1, 2, and 3, the longitudinal members 151 are preferably channel shaped with their web portions 152 welded to overlapping webs of the vertical stiffeners. The longitudinal members 151 are formed with their upper flanges 153 continuous and relatively narrow with their edges welded to adjacent corner of bulged portions 147, and their lower flanges 154 relatively wide and discontinuous, as best indicated in Figure 1, being cut away to straddle the intersecting stiffeners and welded thereto and the door panel 141.

Thus assembled, the intersecting channel sections vertically and horizontally of the door, constitute with the door panel 141, box sections of great rigidity to distribute the loads imposed uniformly between the ends 90

of the door. Due to the proportions and purpose of the clearance opening 140 in the door panel, it becomes necessary to establish continuity of the box girder sections formed 5 by the union of channel longitudinal members 151 and door panel, across that portion of the panel 141 lying immediately below opening 140 and between adjacent intermediate stiffeners 143. This may be done by 10 folding back upon itself and welding the portion of the plate removed from opening 140, but preferably by inserting a length of channel section 155 between adjacent stiffeners and welding same to them and the 15 immediate section of the panel to form with associated stiffeners, an offset box girder reinforcement for the door at the hinge edge. The door framing system is completed by the application of an additional longitudinal 20 member 156 of pressed metal channel section extending along the free edge of the door and beyond the inclined end braces 145 to provide door lock engaging portions 157 to be presently described. The channel beam 25 is provided with substantially horizontal upper flange portions 158 disposed at an angle to the door panel 141 and secured to stiffeners 143, 144 and 145, and a downwardly and inwardly flanged lower portion 159, and 30 welded to door panel 141 to form box girders of maximum rigidity between the lock engaging portions 157 before noted. The lock engaging portions are formed preferably by turning up adjacent sections of the upper 35 flange 158 extending from the outer flange 146 of inclined stiffeners 145 to adjacent ends of the beam.

The lock bearing flanges 157 are welded at their respective inner ends to adjacent 40 stiffeners 145 and reinforced at their outer ends by gussets 160 welded thereto and adjacent ends of upper flanges 158 of the beam. The flanges 157 are backed up by reinforcing brackets designed to close the open ends of 45 the beam, the brackets being of Z-shape with securing flanges 162 welded to adjacent flanges 146 of stiffeners 145 and outer securing end closure flanges 163 welded to adjacent edges of the beam, as best shown in Figures 1 and 2, the web 161 of the brackets extending between said securing flanges to close the space between adjacent beam flanges 158 and 159, to thereby provide a 50 rigid box beam extension for engagement with the door locking devices on the car. As before stated, the doors are hung upon hinge sections 109 forming part of the respective intermediate sloping floor plates 101. The sections 109 are indicated as 55 separately formed pressed metal members extending continuously across the car between adjacent outside hopper sheets. They serve at once to provide mountings for the several doors and to reinforce the floor plates 101 60 defining the upper edge of the respective

door openings. The sections are of general channel configuration with an attaching flange 164 and door bearing flanges 165 and 166 beneath it. The flange 166 has an upturned marginal edge portion 167 designed 70 to engage the door hinge connection 150 supporting the doors for pivotal movement. The connection 150 is cylindrical in form, preferably tubular to save weight, and disposed in sections end to end between the 75 center sill 10 and respective car sides. The connection is introduced between the door hinge flange 148 and underlying flange 166 of the hinge section 109 on the car and their respective curved edges 149 and 167. The 80 hinge parts are so proportioned with respect to each other that with the intervening connection 150 in position between them as indicated in Figures 4, 5, and 6, the hinges will be held from separation in all positions of 85 the door.

With the door closed as indicated in Figure 6, hinge flanges 166 and 167 will be entered in the groove 168 complementing the bulged upper section 147 of the door panel 141. Flanges 166 and 167 will engage adjacent portions of the groove to limit upward and inward movement of the corresponding flanges 148 and 149 on the door, whereby the hinge parts will be held from separation by 90 the intervening bulk of tubular connection 150 which, in position, will prevent the passage of the overhanging curved flange 149 of the door hinge thru space 169 between connection 150 and adjacent floor plates of 95 the car by virtue of the engagement of the door plate 141 at the groove position with adjacent flange 166 of section 109.

The relation between the hinge parts with the door hanging normally open as shown 100 in Figure 5, indicates a slight movement of the connection 150 inwardly and away from curved edge portion 167 by rolling or sliding under the weight of the door as the door swings from the closed position illustrated 105 in Figure 6. During this movement of the connection the curved edge 149 of overhanging door hinge flange 148 will enter the space 170 between the connection and inner face 110 of flange 165 of the hinge on the car, in position to engage said flange as depicted in Figure 5. In this position, the curved edge 167 of flange 166 on hinge section 109 will 115 engage door panel 141 in groove 168 to at all times maintain a proper operating relation between the hinge sections on car and door whereby the edges of curved flanges 149 and 167 will be prevented from biting 120 into the metal of respectively adjacent hinge portions, and thus protected from possible distortion under load. This operating relation continues until the door has reached its limit of opening movement whereupon the door hinge flange 148 will engage the hinge 125 130

part 164 on the car and the door held from abnormal movement under lading thrust.

From the foregoing, it will be noted that the doors are pivotally hung and held in operative position upon associated hinge members on the car by interposing a bar or tube between the hinge on the door and that on the car and may be removed by the mere withdrawal of the interposed bar, as before outlined.

Obviously, the particular type of hinge described may be adapted to function as an interlocking joint between contiguous members in fixed relation, as between walls, roof, 15 and floor sections of knockdown containers and the like, and such construction is contemplated within the scope of the invention.

We claim:

1. In a dump car, the combination comprising doors pivotally hung transversely of the car from side to side and provided with an intermediate opening at the hinged margin thereof to receive a center sill, said marginal portion upon opposite sides of said opening having outwardly bulged rigidifying portions formed to provide door hanging flanges, an associate hinge member on the car having a flange portion adapted to underlie said door hinge flange, and interlocking means intermediate said flanges for pivotally retaining said doors.

2. In a dump car, the combination comprising doors pivotally hung transversely of the car from side to side and provided with 35 extended integral hinge portions formed along the upper margins thereof with flanges projecting rearwardly of the door panel and terminating in curved marginal portions adapted to pivotally support the doors, supplemental hinge portions on the car having curved marginal flange portions adapted to underlie said door flanges, and common interlocking means intermediate said flanges for operably retaining said doors.

45 3. A door for dump cars comprising a single base plate member having parallel longitudinal edges and inclined marginal end portions, integral hinge flange portions extending along the upper margin of the plate, 50 hollow stiffening members reinforcing the upper margin of the plate and terminating at the inclined marginal end portions of the door, a hollow beam secured along the lower margin of the plate and extending with its 55 opposite ends beyond the inclined edges of the door to provide door lock bearing portions, and hollow stiffening members connecting said longitudinals across the panel, said stiffening members forming with said 60 panel box girder reinforcements, all united by welding.

4. A door for dump cars, comprising a single base plate member having parallel longitudinal edges and an integral hinge 65 flange portion extending along one of said

edges, hollow stiffening members reinforcing said hinge and the free edge of the door, the latter extending with its opposite ends by the ends of the door to provide door lock bearing portions, and hollow stiffening members connecting said longitudinals across the panel, said stiffening members forming with said panel box girder reinforcements, all united by welding.

In witness whereof we have hereunto set our hands this 10th day of October, 1931.
